UNITED STATES PATENT OFFICE

2,368,362

ADJUSTING DEVICE FOR MOTOR
BRACKETS

Robert A. Johnstone, Cincinnati, Ohio

Application October 18, 1943, Serial No. 506,684

1 Claim. (Cl. 74—242.14)

This invention relates to a device for adjusting a bracket arranged to support an electric motor.

Motor-driven machines usually have the power imparted to them through a belt drive. My invention contemplates means for quickly and accurately tightening the tension on the belts as they wear or stretch.

The object of my invention is to provide a movable motor support bearing against a cam.

A further object is to provide a ratchet and pawl with the cam to maintain the cam in adjusted position.

A still further object is to provide means for rotating the cam and means to release the ratchet.

My invention will be further readily understood from the following description and claim and from the drawing, in which latter:

Fig. 1 is a plan view of my improved device.

Fig. 2 is a vertical section of the same, taken in the plane of the line 2—2 of Fig. 1, and

Fig. 3 is a detail section, taken in the plane of the line 3—3 of Fig. 1.

In the exemplification shown in the drawing, the supporting structure 11 is mounted on a column support 12 of a drill press. The motor support 13 comprises a pair of right angle plates 14 and 15 welded together. The plate 14 has a pair of elongated holes 16 for reception of cap screws 17 which are threaded into the supporting structure 11 for clamping the plate in adjusted position. A motor 18 is attachable to the plate 15.

The upper face of the structure 11 is provided with a recess 19 in which a disc 20 is received and is rotatable on a stud 21. An eccentric disc 22 is integral with the disc 20 and has a handle 23 attached thereto to provide means for rotating the discs. A portion of the face of the disc 20 is

provided with ratchet teeth 24 arranged to be engaged by a tooth 25 on a spring pressed plunger 26. A threaded guide bushing 27 is threaded into the support and forms a guide for the plunger 26. A spring 28 normally urges the plunger into engagement with the ratchet teeth. A handle 29 is provided to withdraw the plunger from engagement with the ratchet teeth.

With the device in the position shown in Fig. 1, the belt 30 can be tightened by a movement of the handle in a clock-wise direction or the tension released by a movement of the handle in an anti-clock-wise direction. When turning the handle in an anti-clockwise direction, the plunger handle 29 is pulled out to permit the eccentric and ratchet wheel to revolve in its guide. Upon making adjustments the cap screws 17 are loosened to permit the motor support plate to be moved forward or backward. After adjustment the cap screws are tightened to hold the plate in place against the cam 22.

It will be apparent from the foregoing that I have devised a simple adjustable motor support wherein the belt can be readily and easily adjusted.

Having thus fully described my invention, what I claim as new and desire to secure by Letters Patent, is:

An adjusting device for a motor support, comprising a support, a motor mounting plate slideable in a straight line on said support, a ratchet wheel rotatable on said support, an eccentric on said ratchet wheel engaging the end of said plate, a pull pin engaging said ratchet wheel, a handle for rotating said ratchet wheel and eccentric and cap screws extending through elongated holes in said plate and threaded into said support for clamping said plate to said support.
